UNITED STATES PATENT OFFICE

WILLARD E. JONES, OF HIGHLAND PARK, PHILADELPHIA, PENNSYLVANIA

DESIGN FOR A DOILY

Application filed August 29, 1929. Serial No. 32,617. Term of patent 14 years.

To all whom it may concern:

Be it known that WILLARD E. JONES, a citizen of the United States, residing at Highland Park, Philadelphia, county of Philadelphia, and the State of Pennsylvania, has invented a new, original, and ornamental Design for a Doily, of which the following is a specification, reference being had to the accompanying drawing, forming a part thereof. The figure of the drawing is a plan view of the doily, showing the new design. What is claimed is: The ornamental design for a doily as shown.

WILLARD E. JONES.
